UNITED STATES PATENT OFFICE.

CHARLES W. SPONSEL, OF HARTFORD, CONNECTICUT.

DESIGN FOR A NOZZLE FOR HARDENING APPARATUS.

SPECIFICATION forming part of Design No. 30,345, dated March 14, 1899.

Application filed February 15, 1899. Serial No. 705,583. Term of patent 14 years.

To all whom it may concern:

Be it known that I, CHARLES W. SPONSEL, a citizen of the United States of America, and a resident of Hartford, in the county of Hartford and State of Connecticut, have invented and produced a new and original Design for a Nozzle for Hardening Apparatus, of which the following is a specification.

This invention is a new and original design for a nozzle for hardening apparatus, through which water or other liquid is delivered under pressure against the object or objects to be hardened.

Figure 1 is a plan view, and Fig. 2 a front view, of my new nozzle design. Fig. 3 is a front view taken on the line 3 3 of Fig. 1. Fig. 4 is an end view looking from the under side of Fig. 2.

This design comprises a hollow distributing-head 10, with an annular series of branch pipes 11 extending therefrom and encompassing a space substantially concentric with

the distributing-head 10. The latter is provided with an external opening 13 and with an annular chamber 12, which communicates with the interior of each of the branch pipes 11. These pipes are each provided with a slot 14 facing inwardly upon the space encompassed by them.

The leading essential feature of my design is the annular distributing-head having the annular series of hollow branch pipes extending therefrom provided with inwardly-facing openings.

I claim—

The design for a nozzle for hardening apparatus herein shown and described.

Signed by me, at Hartford, Connecticut, this 10th day of February, 1899.

CHARLES W. SPONSEL.
